UNITED STATES PATENT OFFICE.

CHARLES A. WATSON, OF PITTSBURGH, PENNSYLVANIA.

PHOTOGRAPHIC-PRINTING MACHINE.

1,284,507.

Specification of Letters Patent. Patented Nov. 12, 1918.

Application filed May 9, 1918. Serial No. 233,426.

To all whom it may concern:

Be it known that I, CHARLES A. WATSON, a citizen of the United States, residing at Pittsburgh, in the county of Allegheny and 5 State of Pennsylvania, have invented certain new and useful Improvements in Photographic-Printing Machines, of which the following is a specification.

This invention relates to improvements in 10 photographic printing machines, and more particularly to machines of this class adapted to print upon sensitive paper from a film negative.

The principal object of the present invention is to provide a machine of this character 15 that will eliminate the necessity of trimming the prints, by providing means for centering the sensitive paper on the negative and providing means for forming a mat around 20 the negative.

Another object is the provision of lever operated clamping members for engaging and holding the film negative in position on the device, and such members forming a 25 guide for the print paper when they are operatively engaged on the negative.

A further and important object is to provide a clamping member for gripping the paper before the platen is lowered, so as to 30 prevent such paper from being dislodged or moved with respect to the film, before the platen engages the same.

Still another object is the provision of 35 novel lever operating mechanism for operating the several clamps and the platen to permit such parts to be operated by the foot of the operator, thus leaving his hands free to handle the print paper, etc.

With the above and other objects in view, 40 the invention consists of the novel features of construction, combination and arrangement of parts hereinafter fully described and claimed, and illustrated in the accompanying drawings, in which—

Figure 1 is a top plan view of the lamp box top plate;

Fig. 2 is a bottom plan view of the same; and

Fig. 3 is a fragmentary side elevation of 50 complete device partly in section.

Fig. 4 is a sectional detail view showing the double glass pane with the interposed mat.

Referring more particularly to the drawings, the numeral 2 designates the top of a

stand or table having a recess 3 formed therein for the reception of a lamp box member 4 which embodies my improved structure.

A flat metallic top plate 5 is secured to the box 4 and is cut away, forming a recess 6 to allow the light rays to pass out. The edges of the recess 6 are cut away to form supporting flanges for a glass pane 7 which is composed of two pieces of glass having a mat 8 therebetween, as in Fig. 4. Particular attention is directed to the formation of the glass pane 7, such construction providing a perfectly smooth surface for sliding the work over.

Clamping members 9 and 10 are hingedly 70 mounted along the one side and end respectively of the recess 6.

The member 9 is pivotally or hingedly mounted in bearings 11, and has projecting lever arms or lugs 12 and 13 thereon. The 75 lugs 12 and 13 are adapted to have their free ends slidably mounted over pins 14 and 15 respectively, and a coil spring 16 is mounted under the lugs around pins 14 and 15. The springs are adapted to be under sufficient 80 tension to firmly hold the member 9 against the plate and to return the same to its lower position after it has been raised by its co-operating lever mechanism.

The member 10 is pivotally or hingedly 85 mounted in bearings 17 and has a projecting lug or lever arm 18 extending to the rear of the pivot similar to the construction of the lug 12 of member 9. The lug 18 has its free end slidably mounted on a pin 19 and 90 a coil spring member 20 is disposed around such pin and between the plate and lug for providing a constant tension on the member 10.

The pins 14 and 19 pass freely through 95 the plate 5 and are joined at their lower ends under plate 5 by bar 21 held in position by nuts 22.

An eccentric crank lever member 23 is mounted in bearings 24 on the under side of 100 plate 5 and has a hand lever or gripping portion 25 formed on one end and extending upwardly through a suitable slot in such plate, and has its other end bent upon itself as at 26, forming a projection adapted to 105 bear against the bar 21 as such shaft is rocked in its bearings 24. It will be understood that lever 23 is an eccentric crank so that it may be pulled past center and bear against the bar 21 and hold the clamps 9 110

and 10 in their raised position until released. The bar 21 has a screw threaded rod 27 secured thereto adapted to be connected to suitable pedal mechanism 27^a and 5 permits of the operation of the clamps 9 and 10 by the movement of the operator's foot, or by means of the independent hand lever 25 formed on the one end of the crank member 23.

- 10 The clamps 9 and 10 are positioned accurately and form a right angled guide and stop for the print paper, which permits the operator to use the correct size of paper and to position the same accurately over the 15 negative, thus eliminating the necessity of using oversize paper and trimming after printing.

A print paper clamp 28 is mounted along the rear side edge of the aperture or recess 20 6, and comprises a plate 29 which has a downwardly projected extension 29' adapted to bear on the paper. The plate 28 is mounted upon pins 30 slidably mounted in the plate 5 and having their lower ends joined 25 by tie plate 31. The paper clamp is normally held out of engagement with the paper by means of a leaf spring 32 which bears against the plate 31 thus forcing the whole clamp upwardly.

- 30 The clamp 28 is adapted to be forced down into engagement with the print paper to temporarily hold it in position by means of a crank lever 33 supported in bearings 34 on the under side of plate 5. One end of 35 the lever 33 is in engagement with the plate 31 and the other end extends upwardly through the plate 5 and is provided with suitable operating handle 35. The operator, by grasping the handle 35 and rocking the 40 crank lever 33, will force the clamp 28 down into engagement with the paper to hold it against accidental movement until such paper is firmly engaged by the platen A (to be described) when the clamp 28 may be released.

The platen A consists of a back plate 37 to which is movably connected the negative-engaging plate or platen proper 38, through screws or other suitable means 39; and the 50 platen 38 is normally held distended by leaf springs 40 interposed between the same and the back plate 37.

The back plate 37 is hingedly supported in bearings 41 secured to plate 5 and has an 55 operating lever arm 42 extending rearwardly and connected to connecting rod 43 which in turn is suitably connected to an operating pedal 44. Platen A is normally held in a raised position by the tension of a spring 45 connected to rod 43, thus providing for automatically raising the platen when pressure is released from the pedal 44.

It will thus be seen that after the negative and print or sensitive paper are in position, the platen A may be lowered by the

operator by stepping on pedal 44 and that upon releasing such pressure the platen will automatically rise.

The platen 38 has a slight recess 46 on its rear edge to permit the free movement of 70 the clamp 28 so the same may be released when the paper is engaged by the platen.

The operation of the device is as follows:

The parts being assembled in an operative position, and it being desired to print copies 75 of a negative, the negative will be placed over the glass so that the portion having the image thereon is properly positioned with respect to the mat 8. The clamps 9 and 10 are then raised, either by the operation of 80 pedal connected with the rod 27 or by the operation of the eccentric crank lever 25, and the edge of the negative is placed under these clamps, and the clamps then released. If the negative has been properly 85 positioned with respect to the mat 8, the sensitive paper is then slid along the glass 7 until its edges abut the edges of the clamps 9 and 10 which form a right angled guide, and the temporary paper clamp 28 is then 90 forced downwardly by the movement of the crank lever 33 and held in this position. The operator will then tramp or rock the pedal 44, thus forcing the platen A down into engagement with the paper, and the 95 printing process will be carried out while the platen is in this position. When the platen reaches its lowermost position or is firmly in engagement with the paper, the clamp 28 is released and will move upwardly to its normal free position.

When the negative and paper have been exposed a sufficient length of time to the printing light, the pressure is removed from 105 pedal 44 and the platen will automatically rise, thus allowing ready removal of the sensitive or print paper.

It will be understood that this operation may be repeated a number of times and that either a single print or a number of prints 110 may be taken from the negative without removing such negative from its position under the clamps 9 and 10.

Having thus described my invention, what I claim is:—

- 115 1. In a photographic printing machine, the combination with a lamp box, of a top plate having an opening therein, and a glass arranged in said opening, of a clamp member arranged along one side of said opening, a second clamp member arranged along the one end of said opening, said clamps extending over and on to said glass, means connecting said clamps to cause a simultaneous movement thereof, means for operating said clamps, a third clamp arranged to operate over said first-named clamp and adapted to hold the print paper, means for operating said last-named clamp, and a platen arranged to be forced down to en- 120 125 130

gage the print paper, said last-named clamp adapted to be released when said platen is in position.

2. The combination with a lamp box, of a photographic printing machine, of a top plate having an opening therein closed by a transparent member, a clamp member arranged along the one side of said opening, a second clamp member arranged along one end of said opening, said clamp members extending over upon said transparent member and forming a right angled square edge to guide print paper into position, means connecting said clamps to cause simultaneous operation thereof, means for operating said clamps, a third clamp arranged to operate over said first-named clamp to temporarily hold the print paper, lever means for operating said clamp, and a platen adapted to be forced downwardly to engage the print paper, said platen having its rear edge recessed to permit said last-named clamp to be released while said platen is in close engagement with said print paper.

25 3. In a photographic printing machine, the combination of a frame, a lamp box mounted in said frame provided with a top plate having an opening and a slot formed therein, a transparent closure for said opening, a clamp member arranged along the one side of said opening, a second clamp member arranged along the one end of said opening, means connecting said clamps to cause the same to operate simultaneously, means 30 for operating said clamps, a third clamp arranged to operate over said first-named clamp to hold the print paper, a crank lever mounted in bearings secured to the under side of said plate and having a hand engaging portion extending upwardly through the slot formed in said plate, and having its other end in engagement with said last-named clamp, said lever being adapted to force said clamp downwardly to temporarily hold the print paper in position, a 35 pedal and a platen having lever connection with said pedal adapted to be forced downwardly to engage said print paper, said platen being arranged to allow said last-named lever to be released.

40 4. In a photographic printing machine, the combination with a lamp box, of a top plate having an opening therein, and a glass arranged in said opening, of a clamp member arranged along one side of said opening, a second clamp member arranged along the one end of said opening, said clamps extending over and onto said glass, an eccentric crank lever for operating said clamps, said lever being so positioned that it will hold said clamps in a raised position when it is rocked past center, a third clamp arranged to operate over said first-named clamp and adapted to hold the print paper,

means for operating said last-named clamp, 65 and a platen arranged to be forced down to engage the print paper, said last-named clamp adapted to be released when said platen is in position.

5. In a photographic printing machine, 70 the combination with a lamp box, of a top plate having an opening therein, and a glass arranged in said opening, of a clamp member arranged along one side of said opening, a second clamp member arranged 75 along the one end of said opening, said clamps extending over and onto said glass, spring members arranged to normally hold said clamps in position against said glass, an eccentric crank lever for 80 operating said clamps, said lever being so positioned that it will hold said clamps in a raised position when it is rocked past center, a third clamp arranged to operate over said first-named clamp and adapted to 85 hold the print paper, means for operating said last-named clamp, and a platen arranged to be forced down to engage the print paper, said last-named clamp adapted to be released when said platen is in position. 90

6. In a photographic printing machine, the combination with a lamp box, of a top plate having an opening and a slot formed therein, and a glass arranged in said opening, of a clamp member arranged along one 95 side of said opening, a second clamp member arranged along the one end of said opening, said clamps extending over and onto said glass, lever arms secured to each of said clamps, link members secured to said lever 100 arms and extending downwardly through said plate, a cross bar secured to the lower ends of said link members, an eccentric crank lever mounted on said plate and having its one end bearing against said cross 105 bar, and its other end terminating in a handle above said plate, a rod secured to said cross bar and to a pedal to provide for foot operation of said clamps when desired, a third clamp arranged to operate over said 110 first-named clamp to hold the print paper, a crank lever mounted in bearings secured to the under side of said plate and having a hand engaging portion extending upwardly through the slot formed in said plate, and 115 having its other end in engagement with said last-named clamp, said lever being adapted to force said clamp downwardly to temporarily hold the print paper in position, a pedal, and a platen having lever connection with said pedal adapted to be forced downwardly to engage said print paper, said platen being arranged to allow said last-named lever to be released. 120

In testimony whereof I hereunto affix 125 my signature.

CHARLES A. WATSON.
